UNITED STATES PATENT OFFICE.

WILLIAM H. SAUVAGE, OF FLUSHING, NEW YORK, ASSIGNOR TO GOULD COUPLER COMPANY, A CORPORATION OF NEW YORK.

SLACK-ADJUSTER.

1,227,960.

Specification of Letters Patent.

Patented May 29, 1917.

Application filed January 25, 1916. Serial No. 74,196.

To all whom it may concern:

Be it known that I, WILLIAM H. SAUVAGE, a citizen of the United States, and resident of Flushing, in the county of Queens and 5 State of New York, have invented certain new and useful Improvements in Slack-Adjusters, of which the following is a specification.

This invention relates to slack adjusters, 10 and in its more intense aspect to automatic slack adjusters particularly adapted for use in connection with the truck brake rigging of railway cars, although it is, of course, to be understood that without material modification many features of the invention are 15 applicable to the foundation rigging adjacent the power cylinder.

One of the objects of the present invention is to provide a simple and practical automatic slack adjuster which will be reliable 20 and efficient in use and operation. A further object is to provide an automatic slack adjuster having relatively few parts which will be inexpensive to manufacture and so 25 positioned and arranged as to insure predetermined brake shoe clearance as well as uniform piston travel under all conditions.

Other objects will be in part obvious from 30 the annexed drawings and in part indicated in connection therewith by the following analysis of this invention.

This invention accordingly consists in the features of construction, combination of parts and in the unique relations of the 35 members and in the relative proportioning and disposition thereof, all as more completely outlined herein.

To enable others skilled in the art so fully 40 to comprehend the underlying features thereof that they may embody the same by the numerous modifications in structure and relation contemplated by this invention, drawings depicting a preferred form have been annexed as a part of this disclosure, 45 and in such drawings, like characters of reference denote corresponding parts throughout all the views, in which—

Figure 1 is a side elevation of a truck and

associated brake rigging; certain parts being partly in section or broken away in 50 order to more clearly illustrate the present invention as applied thereto;

Figs. 2 and 3 are detail views of certain groups of parts.

Referring now to the drawings in detail 55 and more particularly to Fig. 1, 5 denotes a truck bolster and frame as shown in dotted lines of an ordinary car truck having an adjustable hanger 6 at one side thereof pivotally connected at the point 7 to the upper 60 end of a dead lever 8. The lower end of this dead lever 8 is connected at the point 10 to one end of a non-extensible push rod 11 the opposite end of which rod is connected at the point 12 to the lower end of 65 a two part live lever. This live lever which will hereinafter be described in detail may for the present be considered of one piece of usual construction connected at its upper end 13 to a pull rod or other brake actuating mechanism 14. Both levers are provided with struts 16 and 17 associated with 70 brake beams; if the mechanism is applied to a brake beam truck as shown, adapted to carry shoes coating with the peripheries 75 of the wheels in the usual manner.

Adjacent the bolster 5 is a lug 18 having a rod 20 projecting toward the left, passing through a lug 21 upon the live lever and having a head 22 at its end. Between the 80 lug and head and coiled about the rod 20 is a spiral spring 23 so positioned and arranged as to cause a return of the live lever to normal position on release of the braking power.

Temporary take up and holding mechanism is interposed between the live and dead levers and comprises a rod 24 having a pivotal connection at the point 25 with the strut 16 and a lost motion connection at the 90 opposite end. This lost motion device includes a pair of depending lugs 26 and 27 between which is a friction clamp 28 firmly but yieldingly secured to the adjusting rod 24. The difference in distance between the 95 lugs 26 and 27 and width of clamp 28 con-

stitutes a device providing for predetermined brake shoe clearance. This distance may be varied if so desired by the interposition of one or more washers 30 between 5 this clamp 28 and one of the stops.

In the present case the excess travel due to the wear of the parts of the brake rigging is temporarily taken up and held by this device as the friction clamp 28 will slide relatively along the rod 24 when such excess travel takes place. In order, however, to permanently take up this slack registered by the temporary mechanism, a positive holding device is secured adjacent the point 10 of connection 25 or between the two parts 15 of the live lever, the angular relation of which, is progressively changed as the excess travel is taken up.

The lower part of the lever as shown 20 more clearly in the detail views comprises two similarly shaped members 31 provided with ratchet disks 32 at their upper ends adapted to be engaged by a bifurcated pawl 33 mounted at 34 upon 25 the upper part 2 of the live lever and held in engagement with the ratchet teeth by means of a spring 35 or the like. The parts are so positioned and arranged as to prevent a change of relative angular disposition of the parts 31 and 2 constituting the live lever, during an application of the brakes yet permit excess travel to be taken up and permanently registered by the teeth of the ratchet on release of the brakes.

35 The device operates in substantially the following manner: An application of the brakes will cause a movement of the upper part 2 of the live lever toward the left and by reason of the pawl and ratchet connection 40 between the parts of the live lever, motion will be transmitted through the push rod 11 to cause a corresponding movement, in the opposite direction, of the dead lever 8 substantially in the manner common to 45 brake rigging mechanism of this broad general type. If, however, excess travel takes place exceeding that provided for by the lost motion device adjacent the strut 17 a relative slipping will take place between the 50 friction clamp 28 and the adjusting rod corresponding to this excess travel and the brake beams will move relatively apart. On release of the brakes, the shoes will first drop away from the wheels an amount corresponding 55 to the predetermined brake shoe clearance and continued action of the return spring 23 will force the upper part of the lever about the pivot point 25, thus changing the angular relation between the 60 upper and lower parts of the live lever and permanently record the excess travel upon the teeth of the ratchet.

While the invention above described has

been shown as applied to the brake truck 65 rigging it may however be transposed to the foundation brake rigging if so desired by substituting the piston of the power cylinder for the pull rod 14 and connecting the remaining portions of the brake rigging to the parts of the live and dead levers substantially in the usual manner. The present invention is therefore believed to be simple, practical and reliable and to accomplish, among others, all of the objects and advantages above set forth. 75

Without further analysis, the foregoing will so fully reveal the gist of this invention that others can by applying current knowledge readily adapt it for various applications without omitting certain features 80 that, from the standpoint of the prior art, fairly constitute essential characteristics of the generic or specific aspects of this invention, and therefore such adaptations should and are intended to be comprehended within 85 the meaning and range of equivalency of the following claims.

I claim:

1. In a slack adjuster, in combination, a source of power, a two part live lever connected therewith, temporary and permanent take up and holding mechanisms associated with the live lever adjacent the point of connection between its two parts and a return spring acting on one of said parts of said 95 live lever.

2. In a slack adjuster, in combination, a source of power, a two part live lever connected therewith and temporary and permanent take up and holding mechanism associated with the live lever adjacent the point of connection between its two parts, said temporary mechanism having a yielding friction device associated therewith and so positioned and arranged as to permit 100 105 brake shoe clearance.

3. In a slack adjuster, in combination, a source of power, a plural part live lever connected therewith, and temporary and permanent take up and holding mechanism 110 having means insuring brake shoe clearance associated with the live lever adjacent the point of connection between two of its parts, said permanent take up and holding device comprising a pawl and ratchet mechanism 115 interposed between said two parts of the live lever.

4. In a slack adjuster, in combination, a source of power, a plural part live lever connected therewith, and temporary and permanent take up and holding mechanism associated with the live lever adjacent the point of connection between said parts and having a yielding frictional point of support, said permanent take up and holding 125 device comprising means acting between the

effective ends of the adjacent parts of the live lever adapted to hold the same in the desired angular relation.

5. In a slack adjuster, in combination, a dead lever, a two part live lever, a source of power connected with one of the parts of the live lever, a non-extensible push rod directly connecting the other part of the live lever and the dead lever, temporary take up 10 and holding mechanisms between the live and dead levers, and permanent take up and holding mechanism between the parts of the live lever.

6. In a slack adjuster, in combination, a dead lever, a two part live lever, a source of power connected with one of the parts of the live lever, a non-extensible push rod directly connecting the other part of the live lever and the dead lever, temporary take up 15 and holding mechanism between the live and dead levers, and permanent take up and holding mechanism between the parts of the live lever, said permanent mechanism adapted to permit the variation of the angular relation between the parts of the live lever in one direction only.

7. In a slack adjuster, in combination, a dead lever, a two part live lever, a source of power connected with one of the parts of the live lever, a push rod connecting the other part of the live lever and the dead lever, temporary take up and holding mechanism between the live and dead levers, permanent take up and holding mechanism between the parts of the live lever, and a return spring associated with one of the parts of the live lever adapted to restore the parts to normal position and cause a relative angular movement between the parts of the live lever when excess travel has taken place.

8. In a slack adjuster, in combination, a dead lever, a two part lever, a source of power connected with one of the parts of the live lever, a push rod connected with the other part of the live lever, temporary take up and holding mechanism between the live and dead levers, permanent take up and holding mechanism between the parts of the live lever, and a return spring associated with one of the parts of the live lever adapted to restore the parts to normal position and cause a relative angular movement between the parts of the live lever when excess travel has taken place, said return spring being associated with the live lever and adapted to be distorted from normal position as the brakes are applied.

9. In a slack adjuster, in combination, a support, a dead lever connected therewith, a source of power, a two part lever connected with the source of power, a non-extensible push rod interposed between the ends of the live and dead levers, temporary

take up and holding mechanism yieldingly 65 connected with one of said levers, and positive take up and holding mechanism interposed between the parts of said live lever.

10. In a slack adjuster, in combination, a support, a dead lever connected therewith, a source of power, a two part live lever connected with the source of power, a push rod directly interposed between the live and dead levers, temporary take up and holding mechanism connected with one of said levers 70 and positive take up and holding mechanism interposed between the parts of said live lever, said permanent take up and holding mechanism comprising a ratchet mechanism associated with one of the parts and a pawl 75 coacting therewith mounted upon the other adapted to permit a change in the angular relation between said parts in one direction only.

11. In a slack adjuster, in combination, a live lever, a source of power connected with the live lever, and adjusting mechanism having a frictional connection at one end and adapted to provide predetermined brake shoe clearance, said live lever having two 80 parts adapted to have their relative angular position progressively changed on excess travel of the brake rigging.

12. In a slack adjuster, in combination, a live lever, a source of power connected with the live lever, and adjusting mechanism having a yielding frictional point of support adapted to provide predetermined brake shoe clearance, said live lever having two parts adapted to have their relative angular position progressively changed on excess travel of the brake rigging, one of said parts carrying a ratchet and the other a pawl adapted to coact with the ratchet and slip over the teeth on return of the brake 105 mechanism when excess travel has taken place.

13. In a slack adjuster, in combination, a live lever, a source of power connected with the live lever, and adjusting mechanism adapted to provide predetermined brake shoe clearance, said live lever having two parts adapted to have their relative angular position progressively changed on excess travel of the brake rigging, and a return 110 spring associated with the upper part of the live lever, said return spring being interposed between a relatively fixed support and said live lever.

14. In a slack adjuster, in combination, a live lever, a dead lever, a source of power connected with the live lever, an adjusting mechanism between the live and dead levers having a frictional connection at one end and adapted to provide predetermined brake 120 shoe clearance, said live lever having two parts adapted to have their relative angu-

lar position progressively changed on excess travel of the brake rigging, and a return spring associated with the live lever, a rod on which said return spring is mounted between a lug carried by the live lever and a head on the rod, whereby the spring is distorted on application of the brakes.

15. In a slack adjuster, in combination, a two part live lever, a dead lever, brake beam struts associated with said levers, a push rod connecting the lower ends of the levers,

an adjusting mechanism connecting the levers adjacent the point of connection with the struts, a return spring for the live lever, and means directly associated with the live lever between its parts adapted to permanently take up and hold the excess travel of the brake rigging.

Signed at New York in the county of New York and State of New York this 20 16th day of December A. D. 1915.
